UNITED STATES PATENT OFFICE.

DORSEY F. ASBURY, OF WASHINGTON, DISTRICT OF COLUMBIA.

MEANS FOR PREVENTING GAS INTERFERENCE WITH PROJECTILES IN MULTIPLE-GUN MOUNTINGS.

1,306,368.

Specification of Letters Patent. Patented June 10, 1919.

Application filed November 18, 1916. Serial No. 132,217.

To all whom it may concern:

Be it known that I, DORSEY F. ASBURY, a citizen of the United States, residing at 1437 Euclid St. N. W., Washington, District of Columbia, have invented certain new and useful Improvements in Means for Preventing Gas Interference with Projectiles in Multiple-Gun Mountings; and I do hereby declare the following to be a full, clear, and exact description of the invention, such as will enable others skilled in the art to which it appertains to make and use the same.

My invention relates to means for preventing gas interference with projectiles in multiple gun mountings.

It is well known that the escape of gas from the muzzle of heavy guns, as the projectile emerges from the bore, takes place at such velocity that it will produce erratic flight of the projectile from an adjacent gun which may be fired at substantially the same instant. This gas flows outward and forward in a curved path in all radial directions and forms a figure resembling somewhat a paraboloid of revolution. As its velocity drops eddy currents form and the gas rapidly disperses. As it is the force of the blow which this gas exerts while traveling in the above mentioned parabola, which deranges the flight of the projectile from the adjacent gun it is my purpose to provide means to divert and break up the flow of gas so that it will expend itself without danger of coming in contact with the adjacent projectile.

In the drawings chosen to illustrate my invention, the scope whereof is set forth in the claims,

40 Figure 1 is a front view of a turret multiple gun mounting with the turret omitted and showing the relation of the gas of explosion of one gun with respect to the adjacent gun and with respect to the deck of a ship when my invention is not employed;

45 Fig. 2, a horizontal section of the muzzle end of the right hand gun in Fig. 1 showing in plan the form assumed by the gas of explosion as the projectile emerges from the bore;

50 Fig. 3, a view similar to Fig. 1 showing

my invention incorporated in the multiple gun mounting, and

Fig. 4, a view similar to Fig. 2 with my invention incorporated.

55

Referring to Figs. 1 and 2 10 indicates the gun tube and 11 the muzzle hoop. The outer ends of the tube and hoop register as will be observed and this is the usual construction employed at the present time. By 60 reference to Fig. 1 it will be seen that the gas of explosion 12 of one gun flows across the muzzle of the adjacent gun and when both guns are fired at substantially the same moment the gas of explosion of one gun 65 will come in contact with the projectile emerging from the bore of the adjacent gun and produce erratic flight of the adjacent projectile. It will also be observed that the gas 12 will come in contact with the 70 deck 13 and in many instances has caused the deck to buckle at the point where the blow was struck.

Referring now to Figs. 3 and 4 which illustrate one form of my invention it will 75 be observed that the muzzle end of the gun tube 10 is disposed inwardly of the muzzle end of the hoop B and thus is produced an extended end 14 of the gun hoop. In this extended end 14 I cut slots 15 at right angles 80 to each other and at substantially forty-five degrees to the horizontal and vertical planes in which the guns train and elevate. By providing the slots 15 I form projecting portions 16, 17, 18 and 19 which act as 85 obstructions to the radial flow of gas in either a vertical or horizontal direction but permit its escape up and down at a forty-five degree angle where it cannot exert any 90 normal pressure either on a projectile which may be fired from the adjacent gun or upon the deck 13 upon which the guns may be mounted.

As the gun tube 10 terminates inwardly of the muzzle hoop the projecting portions 16, 95 17, 18 and 19 will not come in contact with the projectile. Also there will be free escape of gas forward as soon as the projectile clears the gun tube, but lateral flow has been broken up as above described.

100

My invention is applicable to multiple gun mountings where two or more guns are

mounted in the same emplacement, and, for the purpose of economy of weight and space, located so close together as to cause blast interference as previously described. As such mountings are usually formed on board ships of war the invention has been developed with a view to relieving the strain on the deck which has frequently been found sufficient to buckle it down. Were this not considered in the form of invention illustrated and described but two slots 15 in a vertical plane would be sufficient to break up gas interference with adjacent guns.

What is claimed is:—

- 15 1. In a multiple gun mounting, the combination with a plurality of guns, of means associated with each gun for restraining the expansion of the gas of explosion laterally in certain directions whereby the gas of one gun will not act upon a projectile discharged from an adjacent gun to derange the flight thereof when said guns are fired at substantially the same moment.
- 20 2. In a multiple gun mounting, the combination with a plurality of guns, of means for restraining lateral expansion of the gas of explosion in certain directions until the projectiles have traveled a predetermined distance forward of the gun muzzles whereby the gas of one gun is prevented from deranging the flight of a projectile discharged from an adjacent gun when said guns are fired at substantially the same moment.
- 25 3. In a multiple gun mounting, the combination with a plurality of guns, of means for restraining lateral expansion of the gas of explosion in the direction of a plane passing through the axes of the guns until the projectiles have traveled a predetermined

distance forward of the gun muzzles whereby the gas of one gun is prevented from deranging the flight of a projectile discharged from an adjacent gun when said guns are fired at substantially the same moment.

4. In a multiple gun mounting, the combination of a plurality of guns having the muzzle portions of their bores enlarged and provided with lateral openings in their barrels within the limits of the enlarged portions of the bores, said openings being disposed out of a plane passing through the axes of the guns whereby the gas of explosion is restrained against lateral expansion in certain directions to prevent the gas of explosion of one gun from deranging the flight of a projectile discharged from an adjacent gun when said guns are fired at substantially the same moment.

5. In a multiple gun mounting, the combination of a plurality of guns, each of said guns comprising a gun tube and a muzzle hoop extending a predetermined distance forward of the gun tube, said hoop being provided with lateral openings forward of the gun tube disposed out of a plane passing through the axes of the guns whereby the gas of explosion is restrained against lateral expansion to prevent the gas of explosion of one gun from deranging the flight of a projectile discharged from an adjacent gun when said guns are fired at substantially the same moment.

In testimony whereof, I hereunto affix my signature in the presence of two witnesses.

DORSEY F. ASBURY.
